UNITED STATES PATENT OFFICE.

ADIEL Y. DODGE, OF SOUTH BEND, INDIANA, ASSIGNOR TO BENDIX BRAKE COMPANY, OF CHICAGO, ILLINOIS A CORPORATION OF ILLINOIS.

BRAKE SHOE.

Application filed April 16, 1926. Serial No. 102,578.

This invention relates to brakes, and is illustrated as embodied in an internal expanding brake for a motor truck. An object of the invention is to increase the strength of the brake shoes, and especially to do so in a manner permitting them to be made more cheaply, as for example from sheet-metal stampings.

Having this object in mind, an important 10 feature of the invention relates to forming the shoe with a body generally triangular in section, so that the stiffening web with its diverging sides forms a trussed reinforcement for the shoe.

15 While such a construction is not essential, as a matter of economy I prefer to form the shoe of sheet metal, either as one integral stamping or as a plurality of stampings secured together to build up the described 20 shoe. In one desirable arrangement, there are three separate members, one forming the friction face, and the other two secured together to form the web and diverging from each other toward the edges of the friction 25 face. To facilitate fastening these members together, it is desirable that they should be continued as double-thickness portions for short distances beyond the corners of the triangular section.

30 Other features of the invention relate to forming novel anchoring means at one end of the shoe, to providing for pivotally connecting a servo shoe at the other end, and to other novel and desirable arrangements and 35 constructions which will be apparent from the following description of the illustrative embodiment shown in the accompanying drawing, in which:

40 Figure 1 is a vertical section through the brake, just inside the head of the drum, showing the shoes in side elevation;

Figure 2 is a section on the line 2—2 of Figure 1, showing the anchors of the brake;

45 Figure 3 is a section on the line 3—3 of Figure 1, showing the pivotal connection of two of the shoes;

Figure 4 is a section on either of the lines 4—4 of Figure 1, showing the construction of the end shoes; and

50 Figure 5 is a section on the line 5—5 of Figure 1, showing the construction of the central shoe.

The particular brake selected for illustration includes a drum 10 and a backing plate 12, with three shoes 14, 16, and 18. Shoe 14

is anchored by being pivoted at its end on a pin 20, between the ends of shoe 16 and well within the curve of the shoes, while shoe 16 has at its end spaced arms 22 straddling the end of shoe 14 and offset within the curve of the shoes, where the arms are pivotally anchored on a pin 24, thus in effect overlapping the two shoes. Anchors 20 and 24 may, if desired, be connected by a reinforcing plate 26.

60 Shoe 18 is connected to spaced arms at the opposite end of shoe 16, by means such as a pivot 28 having an enlarged head slidably engaging backing plate 12. Shoes 14 and 18 are forced apart to apply the brake, 70 against the resistance of a return spring 30, by means such as a double cam 32 having an end flange confining the ends of the shoes laterally, whereupon shoe 18 turns and forces shoe 16 into engagement with the 75 drum against the resistance of an auxiliary spring 34.

The present application relates to the construction of the shoes, whether they are used in the above-described brake or in a 80 brake of some other type.

Each of the shoes 14 and 18 is formed with its body all in one piece, as shown in section in Figure 4. The cylindrical friction face 38 of the arcuate shoe, provided with 85 any desired lining 40, is in these shoes integral with the stiffening web. The web is in the form of two sections 42 and 44, engaging each other at their inner edges and some distance from their inner edges and riveted or spot-welded or otherwise secured together, and which diverge from each other toward the side edges of the friction face 38.

90 Preferably the diverging sides of the web engage the friction face some distance from its edges, to form double-thickness portions along the edges. It will be seen that this provides a hollow arcuate shoe, generally triangular in section so that the web forms a trussed reinforcement for the friction face, 100 and with double-thickness portions projecting beyond the corners of the triangular section.

At its lower end, the sides 42 and 44 of shoe 18 are flattened together to form an 105 arm mounted on the pivot 28 (Fig. 3), integral sleeves or bushings 46 preferably being formed in the sides to embrace the pivot. Similarly sides 42 and 44 at the lower end of shoe 14 are flattened together to form an 110

anchoring arm which is offset within the curve of the shoe and anchored on pin 20.

- Shoe 16 is built up, according to the same general plan, but including three separate stampings or similar members. Of these, one stamping or band 50 forms the cylindrical friction face, with any desired lining 52, while two stampings 54 and 56 form the stiffening web. Stampings 54 and 56, which 5 may be stiffened at their inner edges by short oppositely-projecting flanges 58, are riveted or spot-welded or otherwise secured together, to form a double-thickness web portion some distance from their inner edges, 10 and then diverge from each other toward the side edges of member 50.

Preferably they engage the inner face of member 50 some distance from its edges, to 20 form double-thickness portions along the edges. Stampings 54 and 56 are secured to member 50 by rivets, by spot-welding, or in any other desired manner. Member 50 may be varied in width without changing stampings 54 and 56, overhanging the stampings 25 more or less, thus making it possible to build up shoes of different widths with the same stampings 54 and 56.

At the anchored end of the shoe, stampings 54 and 56 preferably project a considerable distance beyond the friction face, to 30 form the above-described spaced arms 22 straddling the end of shoe 14 and offset inside the curve of the shoe and there anchored on pivot 24. At the opposite end, the 35 stampings project a short distance beyond the friction face to straddle the end of shoe 18 and be mounted on pivot 28. The metal of the stampings around pivots 24 and 28 may be drawn out to form sleeves or integral 40 bushings 60 embracing the pivots.

While an illustrative construction has been described in detail, it is not my intention to limit the scope of the invention to that particular construction, or otherwise than by 45 the terms of the appended claims. Part of the subject-matter herein claimed is continued from my prior application No. 754,711, filed December 8, 1924.

I claim:

- 50 1. A brake shoe comprising a cylindrical friction part with a stiffening web on its inside having diverging portions engaging the friction part adjacent its edges and forming therewith a trussed shoe generally triangular in section, the stiffening web being arranged for mounting on a pivot at one end.
- 60 2. A brake shoe comprising a cylindrical friction part with a stiffening web on its inside of pressed metal separate from the friction part and having diverging portions engaging and secured to the friction part adjacent its edges and forming therewith a trussed shoe generally triangular in section, the shoe being engageable by an operating

device at one end and being arranged to be pivoted at the other end.

3. A brake shoe comprising a cylindrical band and a separate stiffening web on the inside of the band having diverging sides 70 engaging and secured to the band adjacent its edges, said sides being continued beyond the band at one end and arranged to be pivotally mounted.

4. A brake shoe comprising a cylindrical 75 band, and a pair of separate members secured together at their inner edges and together forming a stiffening web on the inside of the band, which members diverge from each other and engage and are secured to the band adjacent its edges, and which project at one end a substantial distance beyond the end.

5. A brake shoe comprising a cylindrical part and two stiffening parts, the two stiffening parts engaging each other for some distance from their inner edges to form a double-thickness web and then diverging toward the outer edges of the cylindrical part to form a trussed reinforcement therefor. 80

6. A brake shoe comprising separate members forming a cylindrical part and two stiffening parts, the two stiffening parts engaging each other for some distance from 85 their inner edges to form a double-thickness web and then diverging toward the outer edges of the cylindrical part to form a trussed reinforcement therefor.

7. A brake shoe comprising a cylindrical 100 part and a stiffening web therefor having portions diverging from the central plane of the shoe and engaging the cylindrical part some distance inside its edges to form a trussed reinforcement therefor.

8. A brake shoe comprising a cylindrical part and a stiffening web therefor having portions diverging from the central plane of the shoe and engaging the cylindrical part some distance inside its edges and then continued toward said edges in engagement with the inner face of the cylindrical part. 110

9. A hollow arcuate brake shoe having an inwardly-offset arm at its end and generally triangular in section to form a trussed stiffening web between the edges of the shoe. 115

10. An arcuate brake shoe having spaced arms at its end and generally triangular in section to form a trussed stiffening web between the edges of the shoe. 120

11. A brake shoe comprising a cylindrical part and a stiffening web having two sides diverging from each other some distance from the inner edge of the web and engaging the cylindrical part inside of its outer edges. 125

12. A brake shoe comprising a friction face and a stiffening web including diverging sides forming a trussed reinforcement for the friction face and extended beyond 130

the friction face as a pair of spaced anchoring arms.

13. An arcuate brake shoe comprising a friction face and a stiffening web including diverging sides forming a trussed reinforcement for the friction face and extended beyond the friction face as anchoring arms offset within the curve of the shoe.

14. A triangular-section arcuate brake shoe having laterally-extended reinforcing portions along its inner edge.

15. A triangular-section arcuate brake shoe having two laterally-extended oppositely-directed reinforcing flanges along its inner edge.

16. An arcuate brake shoe including three stampings secured together to form a trussed hollow body generally triangular in section, and in part overlapping each other to form double-thickness portions beyond the corner of said triangular section.

17. An arcuate brake shoe including three stampings secured together to form a trussed hollow body generally triangular in section, 25 with a double-thickness portion projecting

some distance beyond each corner of the triangular section.

18. An arcuate hollow brake shoe having a trussed body portion generally triangular in section, with a double-thickness portion 30 projecting some distance beyond each corner of the triangular section.

19. An arcuate hollow brake shoe having a trussed body portion generally triangular in section, with a portion projecting some distance beyond each corner of the triangular section.

20. An arcuate brake shoe including three separate members, the first being a cylindrical member forming the friction face, and the other two being secured together and to the first to form a stiffening web and projecting beyond the friction face at one end to form anchoring means and projecting beyond the friction face at the other end to be 40 connected to a servo shoe. 45

In testimony whereof, I have hereunto signed my name.

ADIEL Y. DODGE.
